UNITED STATES PATENT OFFICE.

EUGENE C. HERTEL, OF EAST CHICAGO, INDIANA, ASSIGNOR TO SINCLAIR REFINING COMPANY, OF CHICAGO, ILLINOIS, A CORPORATION OF MAINE.

OIL-CRACKING STILL.

Application filed November 28, 1921. Serial No. 518,446.

My invention relates more particularly to improvements in oil cracking stills of the general character of that shown in Patent No. 1,285,000 granted to the Sinclair Refining Company on the application of E. W. Isom, November 19, 1918. In such stills the main body of oil being cracked is confined in a still drum provided with means for the escape of the vapors of the cracked oil, and the body of oil is heated by circulating it through a battery of pipes or tubes connected in multiple located in a suitable furnace, the battery of pipes being connected at top and bottom to the still drum, and the bottom connection being provided with a circulating pump by means of which the oil is withdrawn from the drum and forced to the bottom of the heating pipes and upwardly therethrough and back to the drum. My invention relates more particularly to the improvement in means for heating the oil.

The cracking of crude petroleum or its products, such as gas oil, is accompanied by a separation of "carbon" and fixed gas, the amount of which is a function of the temperature and increases very rapidly as the temperature necessary to effect the desired cracking is exceeded. In the usual practice of cracking oils as carried out in stills of the type referred to it has been found desirable to use a temperature of about 700 or 800 degrees Fahrenheit. It is necessary that substantially this temperature be imparted to the oil in the battery of heating tubes in the furnace, and therefore a high temperature of the heating gases is necessary. For high efficiency, and economy, it is desirable to extract from the products of combustion the largest possible proportion of the heat contained therein and at the same time to avoid excessive temperatures in any region of the battery of heating tubes in order to minimize separation of "carbon". The latter is particularly undesirable because such carbon is inclined to deposit upon the highly heated surface at which it is released from the oil forming a coating on the tube walls which in a measure insulates the surface on which the carbon is deposited from the cooling effect of the circulating oil. This aggravates the tendency of the heating tubes to become

superheated in this particular region and to develop hot spots which endanger and sometimes cause the rupture of the walls of the tubes in the region in question, or necessitate the shutting down of the still for the purpose of cleaning the tubes.

For maximum economy and efficiency it is therefore desirable in stills of the character to which my invention relates to distribute the heat absorption as equally as possible through the battery of heating tubes, or at least to avoid excessive heating in any region and provide for effective heat absorption throughout. It is inevitable, however, that the heating gases be at the maximum temperature as they first contact with the oil-containing tubes and that their temperature decline as they circulate between or about the latter and as their heat is absorbed by the oil. With pipes of uniform heat absorptive capacity throughout the battery, therefore, considerably the greater part of the heat of the gases would be absorbed by the tubes of the battery with which the heating gases first come into contact, with the result that such tubes would be subjected to severe overheating while the tubes with which the gases later come in contact would not receive as much heat as desirable. The front tubes, or those nearest the firebox of the furnace and first contacting with the heating gases are subject to the most extreme conditions and normally absorbed the greatest amount of heat. This necessitates frequent renewal of these tubes.

It is one object of my invention to provide a heater of the character described in which the disparity in heating effect between the various tubes in the battery, and particularly the front tubes first exposed to the heating gases and the remainder of the heating surfaces of the still, is reduced to the greatest extent possible, in which the tubes more exposed to severe temperatures and requiring renewal may be more readily removed and replaced, and further, in which the latter tubes may be readily observed and their condition noted so that the still may be shut down before the danger point is reached.

In the drawing accompanying and forming a part of this application I have shown and in the following specification described

a preferred form of the invention. It is to be understood, however, that the specific disclosure is for the purpose of exemplification only and that the scope of the invention is defined in the following claims in which I have endeavored to distinguish it from the prior art so far as known to me without, however, relinquishing or abandoning any portion or feature thereof.

10 Fig. 1 of the drawing represents in vertical longitudinal section a heating furnace embodying the invention; Fig. 2 an enlarged vertical section of a detail showing the upper end of the battery of heating tubes partly in section and partly in elevation; Fig. 3 a side elevation, and Fig. 4 a transverse section of one of the elements for increasing the heat transfer area of the heating tubes, and Fig. 5 an end view of the same; and Fig. 6 diagrammatically represents in elevation and partly in section the invention as applied to a still of the type to which particular reference has been made.

15 In the drawings the heater in which my invention is embodied comprises a furnace having a firebox 1, an uptake flue 2, a down-take flue 3 and a stack flue 4, flues 2 and 3 being connected at the tops thereof and the stack flue connected to heating flue 3 at 20 the bottom of the latter so that the flow of heating gases in the heating flue 3 is generally downward. The battery of heating tubes 5 extends vertically through the heating flue 3, the tubes at their upper ends 25 being connected to a suitable header 6 which is connected to an outlet pipe 7 and supported on I-beams 8 and 9 on top of the furnace. The outlet pipe 7 discharges into the still drum 30. The opening 10 in the 30 top of the furnace through which the tubes extend is sealed by a cover of refractory material 11. The bottom of the heating flue is closed by a baffle of refractory material 12 supported on the tubes and by plates 35 13 resting on said material and on angle bars 14 in the furnace wall. At their lower ends and beneath the floor or bottom of the flue the tubes of the battery are connected to a header 15 to which oil is forced through 40 a pipe 16 connected through a circulating pump 31 to the still drum referred to above. A pipe 32 connects the suction side of the pump 31 with the drum. Baffle plates 17 and 18 give the heating gases from the fire- 45 box a sinuous course between and around the tubes of the battery in their descent through the heating flue to the stack flue. It will be observed that, as the oil flows upwardly through the heating tubes and as 50 the furnace gases flow in a generally downward direction about the tubes and first come in contact with the upper ends of the tubes, the maximum effect of the heating gases is felt in the upper pass through the tubes where the oil is brought to the highest

55 temperature, and the heat of the gases is most efficiently absorbed as the gases circulate about the portion of the tubes containing the entering relatively cool oil just before the gases pass to the stack.

60 The hot products of combustion from the firebox come into contact with the front row of tubes 19 near their upper ends, and these tubes therefore are subjected to the highest 65 temperature and the most severe conditions, and, other things being equal, would absorb the greatest amount of heat therefrom, the temperature of the gases being constantly reduced as they circulate toward the back 70 of the furnace and still further as they circulate through the lower passes between the baffles 17 and 18 and below the latter. In order to relatively increase the heat absorption of the tubes in the rows other than the first and thus more evenly distribute the 75 heat absorption between the front row of tubes in the top pass and the remaining heating surfaces, I greatly increase the heat 80 transfer areas of the tubes other than those exposed in the front row of the top pass.

85 According to my invention, this is accomplished by the means more specifically illustrated in Figs. 3 to 5 of the drawings. This means consists of bands or rings of cast- 90 iron or other metal of large superficial area 95 which are preferably applied throughout so much of the length of said tubes (other than those of the front row) as are exposed to the hot furnace gases, and are preferably formed in two semi-cylindrical sections 100 20-21. The inner bore of the sectional ring is substantially cylindrical and of a size to fit closely the pipe of the still to which it is applied, and the outer surface of the ring is deeply corrugated or provided with circumferential ribs and intermediate recesses, thus providing a very largely increased area 105 in contact with the hot gases. The ring sections are tightly clamped together about the pipe to which they are applied by compression bands 23 which may correspond in 110 number to the corrugations in the ring, or a less number may be used.

115 In the specific form of ring shown there are three compression bands applied thereto. As best shown in Figs. 3 and 4 the compression bands are composed of two members, one 23^a of which encircles three-quarters of the circumference of the ring, and the other of which 23^b fills out the remaining quarter 120 of the circumference, the two sections being drawn tightly together by screws 24 extending through lugs 25-25 on the shorter section and passing to lugs 26-26 on the longer ring section.

125 According to my invention, all the tubes except those of the front row are covered by these bands, but the front row of tubes is left bare whereby the greater heat absorption of the front tubes due to the high tem- 130

perature of the gases when they come into contact therewith is to a considerable extent compensated for or offset by the large external surface exposed to absorption of heat 5 on the remaining tubes. Furthermore by leaving the front row of tubes bare any hot spots which may develop therein may be immediately detected by inspection through peep-holes provided in the furnace for that 10 purpose.

For the purpose of promoting uniformity of heat distribution throughout the battery of heating tubes in accordance with my invention, the rings need be omitted only from 15 the length of the front tubes in the top pass of the heating flue, but by leaving the tubes of the front row bare or without rings they may readily be removed and replaced, the headers being formed with hand-holes 27 20 opposite the respective holes 28 which receive the tubes, to facilitate such removal and replacement and also the cleaning of the tubes in position. Normally the holes 27 are closed by plugs 29. To remove the 25 tubes of other than the front row requires considerably more time as the heat-conducting rings will not pass through the openings in the headers but have to be first removed from the pipes. This is not a matter of so 30 much consequence, however, in respect to these tubes as there is very infrequently need for replacement.

I claim:

1. In tubular oil cracking stills, a heating 35 flue, a fire-box connected to one end of the heating flue and a stack flue connected to the other end thereof, a battery of oil heating tubes connected in multiple arranged in and extending through the heating flue 40 whereby heating gases passing from the fire-box to the stack flue pass thereover in the heating flue, means for circulating oil through the oil heating tubes in a direction generally countercurrent to the flow of heating 45 gases thereover, and means arranged on the oil heating tubes in the said heating flue except those nearest the fire-box for increasing the external surface thereof, the oil heating tubes in the said heating flue nearest 50 the fire-box having the minimum external area exposed to heating gases passing through the heating flue.

2. In tubular oil cracking stills, a heating flue, a fire-box connected to one end of the

heating flue and a stack flue connected to 55 the other end thereof, a battery of oil heating tubes connected in multiple arranged in and extending through the heating flue whereby heating gases passing from the fire-box to the stack flue pass thereover in the 60 heating flue, and means for circulating oil through the oil heating tubes in multiple in a direction generally countercurrent to the flow of heating gases thereover, the oil heating tubes in the said heating flue near- 65 est the fire-box having plain cylindrical external surfaces and the remaining oil heating tubes in the said heating flue having corrugated external surfaces, whereby the oil heating tubes in the said heating flue 70 which are nearest the fire-box have the least heat absorptive capacity.

3. In tubular oil cracking stills, a heating flue, a fire-box connected to one end of the heating flue and a stack flue connected to 75 the other end thereof, and a battery of oil heating tubes connected in multiple arranged in and extending through the heating flue whereby heating gases passing from the fire-box to the stack flue pass thereover 80 in the heating flue, the oil heating tubes first exposed to heating gases from the fire-box in the said heating flue having a minimum of external surface exposed therein and the remaining oil heating tubes in the said 85 heating flue having means thereon for increasing the external surface thereof exposed to heating gases passing through the heating flue.

4. In an oil cracking still, a furnace having a heating flue connected at one end to a fire-box and at the other end to a stack flue, a battery of heating tubes connected in multiple arranged in and extending through 95 the heating flue in the furnace, a still drum and connections including a pump for circulating oil therefrom through the heating tubes of the battery in multiple and back to the still drum, baffles in the heating flue for causing heating gases from the fire-box 100 to flow over the heating tubes in a series of passes, and elements on the heating tubes in the said heating flue except those first exposed to heating gases from the fire-box 105 in the front of the first pass in the said heating flue for increasing the external surface thereof.

EUGENE C HERTEL.
